(57) **CLAIM**

The ornamental design for a plastic bag with textured strip, as shown and described.

DESCRIPTION

FIG. 1 is a front elevation of a plastic bag of the present invention;

FIG. 2 is a rear elevation;

FIG. 3 is a bottom plan;

FIG. 4 is a top plan;

FIG. 5 is a right side elevation;

FIG. 6 is a left side elevation;

FIG. 7 is a front elevation of a second embodiment of the invention, the plastic bag having one textured strip extending between the opening of the bag and the bottom of the bag, the rear elevation being a mirror image thereof;

FIG. 8 is a front elevation of a third embodiment of the invention, the plastic bag having one textured strip extending between the opening of the bag and the bottom of the bag, the rear elevation being a mirror image thereof;

FIG. 9 is a front elevation of a fourth embodiment of the invention, the plastic bag having one textured strip extending between the opening of the bag and the bottom of the bag, the rear elevation being a mirror image thereof;

FIG. 10 is a front elevation of a fifth embodiment of the invention, the plastic bag having one textured strip extending between the opening of the bag and the bottom of the bag, the rear elevation being a mirror image thereof;

FIG. 11 is a front elevation of a sixth embodiment of the invention, the plastic bag having one textured strip extending between the opening of the bag and the bottom of the bag, the rear elevation being a mirror image thereof; and,

FIG. 12 is a front elevation of a seventh embodiment of the invention, the plastic bag having one textured strip extending between the opening of the bag and the bottom of the bag, the rear elevation being a mirror image thereof.

The shading in FIGS. 1-12 depicts a texture contrast consonant with the visual appearance shown in these drawings. In FIG. 1, a front panel and a rear panel of the plastic bag are transparent, and a strip of the plastic bag has stippling to show that it has a different texture, and therefore a texture contrast is depicted between the textured strip and the remainder of the bag.

The top, bottom, left, and right views of the alternative embodiments in FIGS. 7-12 are as shown in FIGS. 3-6, except that the plastic bag has the corresponding length and width shown in the embodiments of FIGS. 7-12, respectively.

The broken lines illustrate unclaimed features and define the bounds of the claimed design and form no part thereof.

1 Claim, 11 Drawing Sheets
